UNITED STATES PATENT OFFICE

147,910

DESIGN FOR A PICTURE PROJECTOR HOUSING

Norman T. Knutson, Chicago, Ill., assignor to Bell
& Howell Company, Chicago, Ill., a corporation
of Illinois

Application March 14, 1947, Serial No. 137,611

Term of patent 14 years

(Cl. D61—1)

To all whom it may concern:

Be it known that I, Norman T. Knutson, a citizen of the United States, residing at Chicago, in the county of Cook and State of Illinois, have invented a new, original, and ornamental Design for a Picture Projector Housing, of which the following is a specification, reference being had to the accompanying drawing, forming a part thereof.

In the said drawing—

Figure 1 is a top plan view of a picture projector housing embodying my new design;

Figure 2 is a side elevation of the same;

Figure 3 is a front elevation of the same; and

Figure 4 is a rear elevation of the same.

I claim:

The ornamental design for a picture projector housing, as shown.

NORMAN T. KNUTSON.
